DISPLAY STAND

Charles H. Goodyear, Stockton, Calif., assignor
to Fibreboard Products Inc., San Francisco,
Calif., a corporation of Delaware

Application July 20, 1937, Serial No. 154,601

6 Claims. (Cl. 211—135)

My invention relates to a stand for displaying articles, such as glassware; and the broad object of my invention is to provide a stand which will collapse flat for shipment, and which when set up is strong and rigid and so shaped as to effectively and attractively display a comparatively large quantity of glassware or other articles to be displayed.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawings:

Figure 1 is a front elevational view of a display stand embodying the improvements of my invention; and

20 Figure 2 is a plan view of the same.

Figure 3 is a vertical sectional view of the stand, taken in a plane indicated by the line 3—3 of Figure 2. The dotted lines indicate how the shelf sections collapse.

25 Figure 4 is a perspective view showing the internal construction of the stand; the outer concentric walls and the head piece being omitted, and portions of the inner concentric wall and top shelf being broken away to illustrate the construction more clearly.

30 Figure 5 is a fragmentary horizontal sectional view showing the inner concentric wall and the portions of the back wall to which it is fastened. The dotted lines indicate how the arcuate wall 35 collapses flat against the back wall.

Figure 6 is a perspective view of the head piece which was omitted in Figure 4.

Figure 7 is a perspective view looking at the inner side of one of the outer concentric walls, 40 showing a tab by which the wall is locked to the back wall, and also showing the shelf construction.

Figure 8 is a plan view of the blank from which the outer concentric wall and attached shelf sections are folded. Only a part of the blank is shown.

45 In terms of broad inclusion, the display stand embodying my invention comprises a vertical back wall and a plurality of concentric walls standing in front of the back wall. The concentric walls are of different height, stepping up toward the center of the stand; and shelves are provided between the concentric walls for supporting articles to be displayed in arcuate rows of different height. Another shelf is also provided on the inner concentric wall for supporting another article centrally above the rows. A detachable head piece for displaying printed matter is also provided on the stand. The outer concentric walls are detachably mounted on the back wall

so that they may be shipped flat, and the shelves are foldably connected to the walls so that they also collapse. The inner concentric wall is permanently fastened to the back wall, and is adapted to collapse flat against the latter. 5

In greater detail, and referring to the drawings, the display stand embodying my invention is preferably made of sheet material, such as fiberboard, and comprises a back wall 2 having a foldably connected foot flange 3. The back wall is shown with scalloped edges 4 for decorative purposes, but it is understood that the wall may be of any suitable shape or design. The forward part of the stand comprises a plurality of concentric walls 6, 7, 8 and 9 standing in front of the back wall and of different height, stepping up toward the center of the stand. 10

15 These concentric walls carry a series of arcuately shaped shelves 11, 12 and 13 arranged between the walls for supporting articles to be displayed, such as the glass tumblers 14. The shelves are of different elevation and therefore support the articles in rows of different heights; the varying heights selected depending upon the size and nature of the articles to be displayed. 20 A shelf 16 is also provided overlying the inner concentric wall 6, for supporting another article centrally above the rows of articles 14. In displaying a set of glassware comprising a pitcher and tumblers, the arrangement of the pitcher 17 25 on the central shelf above the rows of tumblers 30 provides a very attractive display.

35 The stand also preferably includes a head piece 18 lying substantially in the plane of the back wall and projecting upwardly from it. The head piece is provided with slots 19, as shown in Figure 6, for engaging the upper edge of the back wall with end tabs 21 lying in front of the wall to hold the head piece in position. The head piece preferably carries printing or advertising matter pertaining to the articles being displayed, and may conveniently be replaced with another head piece 40 carrying different printed matter, depending upon the type of articles being displayed.

45 Referring to the details of the display stand construction, Figure 4 shows the inner concentric wall 6 foldably connected to the back wall by in-turned end portions 22 glued to the back wall. This concentric wall normally extends outwardly from the back wall and is semi-circular in shape, 50 but is provided with crease lines 23 so positioned that the wall may be collapsed flat against the back wall. Figure 5 shows in dotted lines how the arcuate wall 6 folds about the crease lines 23 to collapse against the back wall. 55

The inner concentric wall 6 is held in its extended position by a semi-circular panel 24 foldably connected to the back wall and having a series of locking tongues 26 disposed about its peripheral edge for engaging slots 27 in wall 6. 60

This panel holds the curved wall rigidly in its extended position, and when the stand is collapsed the panel folds flat against the back wall. Shelf 16 which overlies wall 6 is also foldably connected to the back wall, and is preferably formed integrally with panel 24 by a connecting piece 28 glued to the back wall. In the collapsed condition of the stand, shelf 16 is folded down over the collapsed inner concentric wall. Shelf 16 is semi-circular in shape and is notched cut at the corners to provide recesses 29 for receiving tabs 21 of head piece 18. The shelf is also preferably provided with an aperture 31 to provide a seat for the pitcher 17 or other article to be displayed.

The outer concentric walls 7, 8 and 9 are formed separately from strips of material, and are fastened to the back wall by locking tabs 32 engaging slots 33 provided in the back wall. Walls 7 and 8 preferably have two locking tabs at each end, and the outermost wall 9, being short, preferably has a single tab at each end. The tabs and receiving slots of the several walls are arranged at different heights, so that it is impossible to get a wall in the wrong position when the stand is assembled. As shown in Figure 2, the outer concentric walls are not smoothly curved, but are preferably provided with crease lines 34 so that the walls are of polygon shape, presenting a plurality of plane surfaces. If desired the inner concentric wall 6 may also be provided with crease lines to give such a shape.

The shelves between the concentric walls, and indicated at 11, 12 and 13 in Figure 2, serve the double function of supporting articles to be displayed and holding the outer concentric walls in position. These shelves are annular in shape to follow the contour of the concentric walls, and are built in sections to provide the annular shape. The shelf sections are preferably formed integrally with and are foldably connected to the concentric walls, so that they also fold flat when the stand is collapsed. Figures 3 and 7 show the construction of the shelf sections, which comprise a pair of parallel shelf plates 36 and 37 foldably connected to a wall; the upper plate 36 being integrally connected to the wall, and the lower plate 37 being fastened to the wall by a gluing strip 38. The outer ends of the shelf plates are foldably connected together by an integrally formed strip 39.

By this parallelogram arrangement the shelf sections fold out flat into the plane of the wall strips when the stand is collapsed. Figure 3 shows in dotted lines the manner of collapsing a shelf section. The shelf sections are slightly wedge shaped, so that the sections fit together into annular shape; and the shelf structures are provided with extending lips 41 for engaging slots 42 in the adjacent wall. Slots 21 of the inner concentric wall preferably serve the purpose of receiving both the tongues 26 of panel 24, and the lips 41 of the adjacent shelf sections.

Upper plates 36 of the shelf sections are provided with apertures 43, through which articles may be inserted to rest upon the lower shelf plate. The upper shelf plates thus serve as guide and seating elements for securely holding the articles being displayed. Suitable lips 44 are also preferably provided on the concentric walls, adjacent each of the shelf sections, to provide additional protection between articles in adjacent rows.

Figure 8 shows portions of a strip or blank from which an outer concentric wall and attached shelf

sections are folded; the particular strip shown being a portion of wall 8. The body of the strip comprises wall 8, and the two locking tabs 32 are shown at the end. Transverse creases 34, dividing the wall into sections, are also shown; and slots 42 for receiving the tongues of adjacent shelf sections are illustrated. The shelf sections on wall 8 are formed by tabs integrally formed with and projecting from the upper edge of the wall. These tabs are divided from the body of the wall by crease lines 46, and a pair of parallel crease lines 47 are provided in the intermediate portions of the tab to form the shelf plates 36 and 37 and the connecting strip 38. Another crease line 48 separates the end portion of the tab to provide the gluing strip 38.

The stand of my invention effectively and attractively displays a comparatively large quantity of glassware or other articles. This display capacity is due largely to the pyramid shape of the stand and the arrangement of the articles in concentric rows, one above the other. While the stand collapses flat for shipment, nevertheless it is surprisingly strong and rigid when set up. The fact that the inner concentric wall is permanently fastened to the back wall, and is held firmly by panel 24, is responsible in large measure for the rigidity of the stand, because this inner wall holds the outer concentric walls in shape.

I claim:

1. A display stand comprising a back wall, a pair of concentric walls standing in front of the back wall and connected thereto, and a shelf foldably connected to one of the concentric walls and interlocked with another concentric wall for supporting articles to be displayed.

2. A display stand comprising a back wall, a pair of concentric walls standing in front of the back wall and connected thereto, and an arcuately disposed shelf between the concentric walls and comprising a plurality of sections foldably connected to one of the walls and interlocked with another wall.

3. A display stand comprising a pair of walls, a pair of parallel shelf plates foldably connected to one of the walls and extending transversely between the walls, a strip foldably connecting the other ends of the shelf plates to hold the latter in parallelism, and means for connecting the shelf structure to the other wall.

4. A display stand comprising a pair of walls, a pair of parallel shelf plates foldably connected to one of the walls and extending transversely between the walls, a strip foldably connecting the other ends of the shelf plates to hold the latter in parallelism, the other wall having a slot therein, and a lip on the shelf structure for engaging said slot.

5. A display stand comprising a back wall, a pair of concentric walls standing in front of the back wall and connected at their ends to the back wall, a panel extending from the back wall and engaging the inner concentric wall for holding the latter in position, and a shelf between the concentric walls for holding the outer concentric wall in position and for supporting articles to be displayed.

6. A display stand comprising separate strips bent and disposed to form a pair of spaced concentric walls, and a shelf foldably connected to one of the walls and interlocked with another wall for holding the walls spaced and for supporting articles to be displayed.
